CLAIM

The ornamental design for a beverage tray, as shown and described.

DESCRIPTION

FIG. 1 is a top plan view of a beverage tray showing my new design;

FIG. 2 is a front elevation thereof, all other side elevations being a mirror image thereof;

FIG. 3 is a sectional view taken along line 3—3 of FIG. 1; and

FIG. 4 is a bottom plan view thereof.

*Fig.1.**Fig. 2.**Fig. 3.**Fig. 4.*
